UNITED STATES PATENT OFFICE

155,162

DESIGN FOR A MANTEL ORNAMENT OR SIMILAR ARTICLE

Albert C. Jensen, Mountain View, Calif.

Application September 26, 1947, Serial No. 141,589

Term of patent 3½ years

(Cl. D29—23)

To all whom it may concern:

Be it known that I, Albert C. Jensen, a citizen of the United States, residing at Mountain View, in the county of Santa Clara and State of California, have invented a new, original, and ornamental Design for a Mantel Ornament or Similar Article, of which the following is a specification, reference being had to the accompanying drawing, forming part thereof.

I claim:

The ornamental design for a mantel ornament or similar article, as shown.

ALBERT C. JENSEN.
